(57) **CLAIM**

The ornamental design for a wearable communication device, as shown and described.

DESCRIPTION

FIG. 1 is a front perspective view of the wearable communication device.

FIG. 2 is a rear perspective view of the wearable communication device.

FIG. 3 is a top perspective view of the wearable communication device.

FIG. 4 is a front view of the wearable communication device.

FIG. 5 is a rear view of the wearable communication device.

FIG. 6 is a right view of the wearable communication device; and,

FIG. 7 is a left perspective view of the wearable communication device.

The broken lines in FIGS. 1-7 depicting the belt are for environmental purposes only forming no part of the claimed design.
